Fig. 1

Fig. 2

Fig. 3

Fig. 4

FIG. 1 is a view in perspective of a tire repair tool embodying my new design;

FIG. 2 is a view in side elevation of the tool depicted in FIG. 1;

FIG. 3 is an end view of the tool of FIGS. 1 and 2; and

FIG. 4 is an end view taken from the end opposite that of FIG. 3.

The characteristic feature of my design resides in the overall appearance of the tire repair tool with specific emphasis on the bifurcated wishbone-shaped tip.

I claim:

The ornamental design for a tire repair tool, substantially as shown and described.
